OUTSIDE PIPE CUTTING TOOL

Lynn W. Storm, Houston, Tex.

Application August 6, 1947, Serial No. 766,523

11 Claims. (Cl. 164—0.6)

1

The invention relates to a washover overshot and outside cutting tool which is adapted to be lowered into a well bore to release and cut a stuck pipe therein.

In present day practice in the drilling of wells by the rotary method wherein a bit is placed on the end of a string of pipe, and a hole drilled in the ground by rotation of the pipe, it is not uncommon for the pipe to become stuck or twisted off in the well bore. The present day practice in recovering the stuck pipe calls for two separate operations. First, a rotary shoe of sufficient inside diameter to go over the stuck drill pipe and its tool joints, is run into the hole on the end of a large diameter pipe sufficient to telescope over the stuck pipe. This large diameter pipe is commonly called a wash pipe and it in turn is attached to a string of drill pipe of sufficient length to reach the depth of the stuck pipe. As the tool progresses downwardly over the stuck pipe, successive lengths of drill string may be added. Upon engagement of the stuck pipe with the rotary shoe, it is necessary to manipulate the string of pipe with respect to the stuck pipe so that the latter mentioned projects inwardly and upwardly into the wash pipe. After this is accomplished the string of pipe, the wash pipe, and the rotary shoe are rotated and lowered so that the shoe tends to dig out material that is sticking to the side of the stuck pipe.

It is common practice during this operation to pump a mud fluid down through the string of pipe, the wash pipe, and out into the formation adjacent the rotary shoe so that the cuttings can be carried away from the vicinity of the operation. This procedure is continued until it is determined that the pipe has been completely freed from the side of the well bore, or until the rotary shoe becomes dull, or when the operator has determined that he has washed down over all of the stuck pipe that he can.

The entire string of pipe is then withdrawn from the well and the rotary shoe is replaced by a cutting off tool commonly called an outside pipe cutter. The cutter is then lowered on the wash pipe and the wash pipe connected to the drill string which is then lowered into the well bore around the stuck pipe until the desired depth is reached at which a cut is to be made. Depending upon the particular type of cutter, the pipe is either raised, or lowered, or rotated, or pumped through to engage a tool joint and to make the cut on the stuck pipe.

If a successful cut is accomplished then the

2

cutter, the washover string, and the drill pipe along with the severed portion of the stuck pipe are withdrawn from the hole, section by section. If an additional length of pipe remains stuck in the well bore, the rotary shoe is replaced on the end of the wash string and lowered into the well bore to cut the formation away from the stuck pipe. After this is completed, the cutter is replaced for the rotary shoe and another cutting operation is attempted. This procedure continues until all of the pipe has been removed from the well.

However, if it is determined by the operator during the making of a cut on the stuck pipe, that a successful cut cannot be accomplished, it is then necessary to try to free the cutting tool from the stuck pipe and remove it from the well bore. In present day tools it is necessary in practicing this procedure, that various elements must be sheared out of the cutting tool before it can be released and retrieved from the well bore. Also, the present day design of cutting tools cannot be used for washing downwardly over the stuck fish since the tools have holes through the body of the cutter and it is therefore impossible to circulate a fluid downwardly through the tool and discharge it adjacent the rotary shoe since the fluid will pass outwardly through the holes in the body above the shoe thereby losing circulation to the bottom adjacent the shoe.

A primary object therefore of the present invention is to provide a combination washover overshot and outside pipe cutter which can release the stuck pipe, cut if off, and retrieve it to the top of the well bore all in one operation.

Another object of the invention is to provide a combination tool having no holes through the body thereof so that the circulation of drilling fluid can be effected downwardly through the tool to discharge it adjacent the rotary shoe on the lower end thereof.

Another object is to provide a combination washover overshot and cutting tool which cutting tool can be engaged and released at will from the stuck fish.

Still another object of the invention is to provide a combination washover overshot and outside pipe cutter which may be released at will from the once engaged stuck pipe, and which may be reengaged with the stuck pipe without damaging or fracturing various elements of the tool.

Another object of the invention is to provide

3

a combination washover overshot and outside cutting tool which is arranged to telescope over a stuck pipe in a well bore.

Another object of the invention is to provide a combination washover overshot and cutting tool, which tool is provided with gripping means to grip the released pipe and cutting means which is arranged to cut the released pipe.

Still another object of the invention is to provide a combination washover overshot and outside cutting tool which is provided with gripping means and cutting means to grip and cut a stuck pipe in the well bore, which means are arranged to normally be in inactive position, but movable to and from engagement with the stuck pipe.

Another object of the invention is to provide a combination washover overshot and cutting tool which is arranged to telescope downwardly over a stuck pipe in a well bore and then to cut the stuck pipe in two, and then to retrieve the cut portion, all in one trip.

Another object of the invention is to provide in a washover overshot, gripping means which are normally retained in inactive position while the tool is telescoping downwardly over the stuck pipe, but which are movable to and from engaging position therewith.

Another object of the invention is to provide in a washover overshot a slip cage and slip means along with a slidable slip holder which is resiliently retained in inoperative position while the overshot is being telescoped downwardly over the stuck pipe, but which holder is movable to engage the slips with the stuck pipe.

A further object of the invention is to provide in an outside cutter, cutter members which are adapted to remain in inactive position while the tool is being lowered over a stuck fish in the well bore, but movable to and from operative position after the pipe has been engaged.

A still further object of the invention is to provide in a cutter, which is arranged to telescope downwardly over a stuck pipe in a well bore, cutter members which are resiliently urged to cutting action against the stuck pipe.

Other and further objects and advantages of the invention will be more readily apparent from a consideration of the following description in connection with the accompanying drawings wherein:

Fig. 1 is a vertical sectional view, partially in elevation, of the upper part of the tool;

Fig. 2 is a continuation of Fig. 1 showing the lower part of the tool;

Fig. 3 is a section taken on the line 3—3 of Fig. 1;

Fig. 4 is a section taken on the line 4—4 of Fig. 2;

Fig. 5 is a vertical sectional view of the upper part of the tool showing the tool engaged with a stuck pipe in the well bore;

Fig. 6 is a continuation of the tool shown in Fig. 5 showing the lowermost part of the tool with the cutters advanced to their centermost position against the stuck pipe;

Fig. 7 is a section taken on the line 7—7 of Fig. 5; and

Fig. 8 is a section taken on the line 8—8 of Fig. 6.

The tool shown in Fig. 1 comprises a body 2 secured by means of threads 3 to a sub 4 which is in turn provided with threads 5 for connection to a suitable length of wash pipe. The sub 4 is splined at 7 to receive slip cage nut 9 cofitting therewith. The slip cage nut 9 is in turn thread-

ed at 10 to the slip cage 11 which is provided at 13 with windows to receive the slips 14. Adjacent the windows 13, the slip cage is tapered inwardly and downwardly at 15 to guide the slips outwardly into engagement with the pipe to be engaged and cut.

The slip holder 17 is slidably arranged on the slip cage and is connected to the slips by means of the rod 18 which is connected at 19 to the slip holder and passes downwardly through the opening 19' in the slip cage 11, and is connected at 20 to the slips 14. A spring 21 is arranged around the rod 18 and rests on the shoulder 21'. The spring 21 abuts against the slip holder or piston 17 and is provided so as to retain the slip holder in an uppermost position so that the slips 14 will be positioned in the windows or on a portion of the bevelled face 15 so that they will not while being lowered contact the pipe to be engaged and cut. The port 22 through the slip cage nut 9 provides access for a pressure fluid to the top 23 of the slip holder 17. A discharge port 24 in the slip cage 11 provides access for a fluid pressure to enter into the space 25 between the body 2 and the slip cage 11 so that an equal pressure will be exerted upon the top 23 and the bottom 26 of the slip cage holder while the tool is being lowered over the stuck pipe in the well.

The lower end of the slip cage 11 is provided with a clutch element at 27 to mate with the clutch element 27' of the drive sleeve 28 which serves as a link between the upper and lower portions of the tool. Drive sleeve 28 is provided with an annular ridge 29 which serves as a stop for spring 30 which is slidably mounted over the drive sleeve. The spring 30 rests on bevelled or tapered sleeve 31 which is slidably mounted relative to the drive sleeve 28 by means of the pin 32 in the guide slot 33. A cofitting bevelled plate 35, immediately below the plate 31, is connected to the ring gear 36 by means of the clutch construction 37. The ring gear 36 is provided with teeth 38 on the lower end thereof, which are arranged to fit teeth 39 on cutter 40 which is pivoted in the body 2 by suitable means such as screws 41. The cutters 40 are provided with replaceable knife inserts 52.

Bearings 43 in the race 44 resting on the annular shoulder 44' immediately below the slip cage 11, are provided to permit relative rotation between the parts as hereinafter described. It is to be noted that the upward travel of slips 14 is limited by the pin 45 therethrough which rests on shoulder 46 of the slip pin pocket 47 which is arranged on the outer periphery of slip cage 11. Downward movement of the slips may be continued until the pin 45 engages the shoulder 48 which is the bottom of the slip pin pocket 47.

In Figs. 5, 6, 7, and 8 the tool is shown in engaging and cutting position in a well bore. In actual operation of the tool it would be connected to a string of wash pipe and the wash pipe would then be connected to a string of drill pipe of the required length to complete the releasing of the stuck pipe from the well bore.

As the tool is telescoped downwardly over the stuck pipe it will be rotated whereupon the rotary shoe 50, which is provided with teeth 51, will cut away stuck material from adjacent the pipe. A mud fluid is circulated downwardly through the tool to discharge at the lower end thereof adjacent the rotary shoe to carry away the cuttings of the earth formation from the tool, and to permit it to descend around the cut pipe.

When the operator has determined that he has telescoped over a sufficient length of stuck pipe, shown in dotted outline in Figs. 1, 2, 5, and 6 at 60, he raises the tool while mud circulation is maintained. When the pressure port 24 is brought opposite a tool joint 60 as shown in dotted line in Fig. 5, the port 22 is then located above the tool joint, thus producing a pressure differential between ports 22 and 24.

Under this condition, greater pressure will be exerted through the port 22 and on to the top 23 of the slip holder 17 than will be exerted on the nether surface 26 through the port 24, since the upper pressure port 22 is adjacent the drill pipe where the fluid is moving at a slower velocity than adjacent the port 24 which is adjacent the drill joint 61'. Due to the difference in the velocity of the fluid adjacent the upper port 22 and that adjacent the lower port 24, a higher pressure area will be created in the lower velocity area. This difference in pressure causes the slip holder 17 to move downwardly whereupon the slips 14 move downwardly and outwardly on to the bevelled surface 15 of the slip cage 11 to engage the tool joint as at 63.

In order to insure a positive engagement of the slips 14 with the tool joint at 63 the operator takes an upward pull upon the string of pipe which firmly seats the teeth 64 as shown in dotted outline in Fig. 7, against the surface of the stuck pipe at 63. Upward movement of the tool serves to position the slip cage 11 downwardly along with the drive sleeve 28, which moves downwardly whereupon the annular ridge 29 being engaged to the spring 30 compresses the spring downwardly. At the same time clutch 7 is separated as shown in Fig. 5 in contrast to its position shown in Fig. 1.

At this stage of operation the slip cage is resting upon the ball race 44 so that relative rotation may be imparted to the body 2 without effecting the engagement of the slips with the stuck pipe. The compression of the spring 30 forces plate 31 against plate 35 to a certain point. Right hand rotation of the tool causes the teeth 39 on the cutters 40 to engage with the teeth 38 in the ring gear 36 so that the cutters are moved outwardly to engage the stuck pipe.

The free rotation of the knife is, however, only momentary and proceeds only to the point that the cutter element 40 contacts the fish whereupon the cutter tends to dig into the fish by the amount of friction built into the cone clutch elements 31 and 35. This point is almost instantly reached and the clutch becomes over-loaded and starts slipping. As the tool is rotated the clutch supplies a continuous given amount of drag to the knife which continues to cut away the fish and advance deeper into the fish with each rotation by virtue of the efforts of the slipping clutch to hold the ring gear stationary. As the cutting progresses the pinion arm or knife combination revolves about its pin 41, the cutting edge always advancing toward the center of the fish until the pipe is severed.

If for any reason the operator determines that he is unable to make his cut on the stuck pipe, the rotation of the tool is reversed and the cutters will back up into retracted position as shown in Fig. 4. If the operator should decide to remove the tool from the well bore, he may disengage the slips 14 from the pipe at 63 by merely stopping fluid pressure momentarily and lowering the tool, which will permit the springs 21 to move the slip holder 17 upwardly, thereby withdrawing the

slips 14 off of the bevelled face 15 and into the windows 13. An alternate method of releasing the tool from the stuck pipe is to lower the tool until the pressure port 22 is adjacent the tool joint 60, while the pressure port 24 is therebelow. The reverse positioning of the two pressure ports causes a pressure differential in such a manner so that the slip holder moves upwardly, thereby disengaging the slips 14 from the fish 60.

Broadly the invention contemplates a combination washover overshot and outside cutting tool which is adapted to be lowered into a well bore for releasing and cutting a stuck pipe there-in and retrieving the cut portion from the well bore.

The invention claimed is:

1. A combination washover overshot and outside cutter for releasing and cutting a portion of a stuck pipe in a well bore comprising, a body, a slip cage releasably connected thereto, a pressure sleeve slidable on said slip cage, slips connected to said sleeve, there being windows with inwardly and downwardly tapered surfaces in said slip cage to receive said slips and for moving said slips outwardly into engagement with the pipe to be cut, a drive sleeve connected to said slip cage, tapered means slidably connected to said drive sleeve, cutters mounted in said body, a tapered sleeve engaging said cutters and arranged to fit said first mentioned tapered means, resilient means engaging said pressure sleeve to normally retain said slips in retracted position, said sleeve being movable by fluid pressure to move said slips to engagement with the pipe to be cut, and means operable when an upward pull is thereafter exerted on said body to frictionally engage said tapered means with said tapered sleeve whereby rotation of said body therewith moves said cutters into engagement with the pipe to be cut.

2. In a washover outside pipe cutter for releasing and cutting a fish stuck in a well bore, said cutter having a rotary shoe thereon, a body, a slip cage slidable in said body and releasably engaged therewith, a sleeve slidable on said cage, slips connected to said sleeve and fitting in said slip cage, there being inwardly and downwardly tapered surfaces on said slip cage for moving said slips outwardly to engage the fish, resilient means engaging said sleeve to normally retain said slips disengaged from said fish, said sleeve being movable by fluid pressure to move said slips outwardly to engage said fish, a drive sleeve connected to said slip cage, a bowl slidably connected to said drive sleeve, a cooperating tapered sleeve there-beneath, said bowl and tapered sleeve being normally in sliding engagement, and means operable when an upward pull is exerted on the overshot after engagement with the pipe to be cut to frictionally engage said bowl and tapered sleeve.

3. A tool for lowering into a well bore to wash over and cut stuck pipe for removal from the well bore comprising, an elongate cylindrical body to wash over such pipe, a gripping member rotatably mounted in such body and movable to and from engagement with such pipe, cutters mounted in said body, a tubular member slidably connected to said gripping member, meshing gearing means on said tubular member and said cutters to move said cutters into and out of engagement with such pipe, said cutters normally retained in inactive position, upward pull on said body frictionally engaging said tubular member and said gripping member whereby rotation of

said body thereafter moves said cutters into engagement with such pipe.

4. An overshot for lowering into a well bore to washover a fish for removal therefrom comprising, an elongate cylindrical body, a tubular slip cage and an elongate tubular sleeve in said body, a piston ring disposed between such body and sleeve and slidable in said body, slips supported by said piston ring and fitting in said slip cage, there being inwardly and downwardly tapered guide surfaces on said slip cage for moving said slips inwardly to engage the fish, and means for releasably supporting said slips in a portion of the guide surfaces where they will not be in engagement with the fish to be gripped, vertically spaced fluid inlet means in said sleeve establishing fluid communication with bottom and top faces of said piston ring, said piston ring being moveable by circulation of fluid in such well bore when said body is telescoped over such fish and the fluid inlet means establishing fluid communication with one face of such piston ring is proximate an enlargement on the fish.

5. A washover overshot adapted to be lowered into a well bore and manipulated therein to engage a pipe comprising, an elongate cylindrical body, a tubular slip cage and an elongate tubular sleeve in said body, a piston ring disposed between said body and sleeve and slidable in said body, slips connected to and movable by said piston ring, said slip cage and slips having cooperating guide and slide surfaces respectively for moving said slips inwardly into engagement with such pipe, resilient means normally retaining said slips in portions of said guide surfaces out of engagement with such pipe, vertically spaced fluid inlet means in said sleeve establishing fluid communication with bottom and top faces of said piston ring, said piston ring being moveable by circulation of fluid in such well bore when said body is telescoped over such pipe and the fluid inlet means establishing communication with one face of such piston ring is proximate an enlargement on such pipe.

6. An outside pipe cutter comprising, a body, a gripping member in said body movable to and from engagement with the pipe to be cut, cutters mounted in said body, a pair of beveled co-fitting sleeves rotatable in said body, one of such sleeves being connected to and actuating said cutters, resilient means connecting such other sleeve to such gripping member and normally urging such last mentioned sleeve into sliding engagement with such first mentioned sleeve, movement of such body relative to such gripping member resiliently and frictionally engaging such pair of co-fitting beveled sleeves whereby rotation of such body relative thereto moves said cutters to and from cutting position.

7. In an outside pipe cutter a body, a gripping member in said body movable by fluid pressure to grip the pipe to be cut, cutters mounted in said body, a pair of beveled co-fitting sleeves in said body, one of said sleeves being connected to and actuating said cutters, the other of said sleeves being connected to said gripping member, said sleeves being normally in slidable engagement but frictionally engageable by an upward pull on said cutter after said gripping member has engaged the pipe to be cut whereby rotation of said body relative to said sleeve moves the cutters to and from cutting position.

8. A cutter tool adapted to be positioned over a pipe in a well comprising a body, a slip cage and slip means having cooperating guide and

slide surfaces respectively, said slip means being normally retained in a portion of the guide where they will not be in engagement with the pipe to be cut but movable to engagement with the pipe at a predetermined time, means to permit relative rotation of said body and gripping member upon movement of said gripping member into engagement with such pipe, cutters mounted in said body, a pair of beveled co-fitting sleeves rotatable on said body, one of said sleeves engaging said cutters, resilient means connecting the other sleeve to said slip cage and normally urging the last mentioned bevelled sleeve into sliding engagement with the first mentioned sleeve, said resilient means being operable upon upward movement of such body relative to such slip cage to frictionally engage said pair of bevelled sleeves together whereby rotation of said body relative thereto moves said cutters to and from cutting position.

9. In a tool to be lowered into and manipulated in a well bore having drill fluid therein, a body, a slip holder slideable in said body having slips connected thereto, said slips being expandable and retractable upon movement of said slip holder, fluid reservoirs in said body above and below and in communication with upper and lower ends of said slip holder, a first port in communication with the fluid reservoir above such slip holder, and a second port spaced from said first port and in communication with the fluid reservoir below said slip holder, said slip holder being moveable by a differential in pressure created by circulating drill fluid when said tool is positioned adjacent a member to be gripped and one of such ports is positioned proximate a restriction in such well bore.

10. The method of actuating a slip assembly in a bore hole having well fluid therein, said slip assembly including a movable piston responsive to fluid pressure differential to which slips are secured and including spaced fluid pressure inlet means providing fluid communication with opposite sides of said piston comprising, positioning said slip assembly in such bore hole adjacent a member to be gripped, positioning that portion of such inlet means providing fluid communication with one side of said piston adjacent a restriction in such bore hole, and circulating drill fluid in such bore hole whereby fluid circulating proximate said inlet means creates a pressure differential on opposite sides of said piston thereby actuating said piston and moving said slips to and from gripping position with such member to be gripped.

11. In a tool to be lowered into and manipulated to grip a member in a well bore, such well bore having drill fluid therein comprising, an elongate cylindrical body, a tubular slip cage and a tubular sleeve in said body, a pressure ring slidably disposed between said sleeve and body, said pressure ring being movable by fluid pressure and having upper and lower piston faces, first fluid inlet means above and in fluid communication with such upper piston face, second fluid inlet means spaced below and in fluid communication with such lower piston face, gripping elements supported by said pressure ring and movable to and from gripping position by said pressure ring, such slip cage and slips having cooperating guide and slide surfaces respectively for moving said slips into and out of gripping engagement with said member, and resilient means disposed between said body and said slip cage and engaging said pressure ring to normally

retain said slips in a portion of the guide where they will not be in engagement with the member to be gripped, said pressure ring being movable by differential in pressure created by circulating such drill fluid when said tool is positioned about the member to be gripped and one of such inlet means is proximate an enlargement on such member.
